UNITED STATES PATENT OFFICE.

WILLIAM MILLS, OF PHILADELPHIA, AND EDWARD B. MOORE, OF WEST CHESTER, PENNSYLVANIA, ASSIGNORS TO SAID MOORE.

BUTTON-HOLE SEWING-MACHINE.

SPECIFICATION forming part of Letters Patent No. 439,599, dated October 28, 1890.

Application filed June 17, 1889. Serial No. 314,673. (No model.)

To all whom it may concern:

Be it known that we, WILLIAM MILLS, of the city of Philadelphia, and EDWARD B. MOORE, of the borough of West Chester, Pennsylvania, and both citizens of the United States, have invented certain useful Improvements in Button-Hole Sewing-Machines; and we do declare the following to be a full, clear, and exact description of the invention, such as will enable others skilled in the art to which our improvements pertain to make and use the same.

Our invention has for its object the simplification and improvement of the class of machines to which it belongs.

In the accompanying drawings, forming part of this specification, we have illustrated our improvements as embodied in a machine and combined with its various operative parts in the way which we believe will be found the best adapted for use, and in the claims we have clearly pointed out those features of the machine so shown which are new with us and which we desire to protect by Letters Patent.

Reference being now had to the drawings, Figure 1, Plate 1, is a plan view of the under side of the feed-slide. Fig. 2, Plate 1, is a sectional view of the feed-slide and disk with pivoted tooth dropped and in engagement with feed-cam or sectional part of worm 11. Fig. 3, Plate 1, is a sectional side view of disk with pivoted tooth 4 elevated above feed-cam or sectional part of worm 11. Figs. 4 and 5, Plate 2, are sectional side views of under side of machine, as at W W, Fig. 9. Fig. 6, Plate 2, is a sectional side view of under side of machine, as at X X, Fig. 9. Fig. 7, Plate 2, is a sectional end view of feed-block 98 with side bearings 100 100. Fig. 8 is a sectional side view of under side of machine, as at Y Y, Fig. 9. Fig. 9, Plate 3, plan view of under side of machine. Fig. 10, Plate 4, is a plan view of a part of the machine with feed-slide removed. Fig. 11, Plate 4, is a perspective view of throat-plate 21 and its support. Fig. 12, Plate 4, is a perspective view of the double-grooved racer-block 57½ for operating lower needle. Fig. 13, Plate 4, is a sectional perspective view of the needle-racer 62, needle-holder 70, and needle

racer-arm 65. Fig. 14, Plate 4, is a sectional perspective view of one end of lever-arm 65, ball-joint 73, for operating lower needle-racer 62. Fig. 15, Plate 4, is a perspective view of lever 75 and slide 77 for operating lower needle-racer 62. Fig. 16, Plate 4, is a view of side cam 61 for vibrating grooved block 57½, in which is operated lower needle-racer 62. Figs. 17, 18, 19, 20, 21, 22, 23, 24, and 25, Plate 5, 60 are perspective, sectional, and plan views of mechanisms connected with feed and trip motions. Fig. 26, Plate 5, is a rear view of the end of arm of machine with take-up arm 122 and bearing 123 and take-up cam 124 carried on rock-shaft 111. Fig. 27, Plate 6, is an end view of the head of machine, take-up arm 122, and cam 127. Fig. 28, Plate 6, is a skeleton side view of machine, showing pivoted block 130 for carrying knife 130½, lever 137, and block 138, wedge 134, and anvil 136. Figs. 29, 30, 31, 32, and 33, Plate 1, are side and perspective views of parts of stop motions.

The following descriptions and references 75 will more fully explain the purposes of the several parts and their relations to each other:

Fig. 1, Plate 1, shows the lower side of the feed plate or slide. 2 is a rotating disk, which carries an ordinary clamp for holding fabrics 80 while being stitched. (Not shown in drawings.) 3 is a segmental rack fastened to under side of disk 2 by screws a' a'. (See Figs. 1, 2, and 3, Plate 1, and Fig. 9, Plate 3.) 4 is a pivoted tooth in segmental rack 3, pivoted 85 at a'. (See Figs. 2 and 3, Plate 1, and Fig. 9, Plate 3.) 5 is a steady-pin fastened to disk 2 and working in slot 5' in said pivoted tooth 4. 6 6 are the side bearings for said pivoted tooth 4. 7 is a projection on pivoted tooth 4. 90 (See Figs. 2 and 3, Plate 1.) 8 is a depressing-rod fastened to end of pivoted tooth 4 at 8' and extending above the surface of disk 2. (See Figs. 2 and 3, Plate 1.) 9 is a spiral spring carried on depressing-rod 8, which 95 tends to depress the end of pivoted tooth 4, that engages with feed-cam or sectional part of worm 11. (See Figs. 2 and 3, Plate 1.) The necessity for these several parts may be further explained as follows: When feed-slide 1 is in position and being fed forward in the process of stitching the first straight side of

- a button-hole, it is necessary that pivoted tooth 4 shall be held above the outer periphery of feed-cam or sectional part of worm 11. This is accomplished by means of plate 10, as shown in Fig. 3, Plate 1; but as soon as the heel of pivoted tooth 4 is fed over the end of plate 10 it is forced down by the action of spring 9, carried on rod 8, and is at once engaged by feed-cam or sectional part of worm 11, as shown in Fig. 2, Plate 1, and by this means disk 2 is given this first movement of rotation and the cam or screw thrown into engagement with the teeth of the rack, so that the bolt is intermittently turned at each revolution of said feed-cam or sectional part of worm 11, carried on main shaft B, at the completion of each stitch in making the round end in the eye of the button-hole. At the completion of the stitching in each button-hole disk 2 is turned by the operator and rod 8 is pressed back, which raises pivoted tooth 4 up to the top of plate 10, and feed-slide 1 is drawn back to its initial position for the commencement of a new button-hole.
- 12 is a sectional flange extending around the outer periphery of segmental rack 3. (See Figs. 1 and 2, Plate 1.)
- 13 is an adjustable pin in arm 14 $\frac{1}{2}$ of rock-shaft 14. (See Fig. 10, Plate 4, Fig. 8, Plate 2, and Fig. 17, Plate 5.) As the feed-slide moves forward, flange 12 on segmental rack 3 comes in contact with adjustable pin 13, and rock-shaft 14 is slightly turned, by which action pawl 18 is lifted out of ratchet-wheel 17 by arm 19 of rock-shaft 14, and thus the forward movement of feed-slide 1 is suspended while disk 2 is being turned, and the round end of the eye of the button-hole is stitched. (See Fig. 8, Plate 2.) At the moment the turning of disk 2 is completed adjustable pin 13 drops off the end of sectional flange 12, and pawl 18 is at once restored to contact with ratchet-wheel 17, as shown in Fig. 17, Plate 5, and feed-slide 1 moves on in stitching the last straight side of the button-hole.
- The general principles embracing flange 12 upon segmental rack 3, carried on disk 2 for raising pawls out of ratchet-wheel, are embraced in Patent No. 349,445, granted to Edward Blackfan Moore and George Rehfuss, September 21, 1886.
- b b b are friction-plates bearing upon the edges of under side of disk 2, and fastened to under side of feed-slide 1 by screws c c c.
- 20, Plate 1, Fig. 1, is a slot or opening in disk 2 and feed-slide 1 for passage of center or throat plate 21, as feed-slide 1 is moved forward and backward in the several operations of clamping and cutting the material and stitching the button-hole.
- 21 is the throat or center plate through which the needles pass in their upward and downward movements. (See Fig. 11, Plate 4, and Fig. 9, Plate 3.)
- 22 is a guide-plate fastened to the under side of feed-slide 1 by screws d d d. 23 is a slot in said guide-plate in which pin 24 car-

rying roller c', (see Fig. 10, Plate 4,) passes as the button-hole is being stitched.

25 25 are male and female shoes fastened to guide-plate 22 and forming part of the guide-slots, and by means of which the size and shape of each button-hole is controlled, as explained in the patent to Moore and Rehfuss No. 349,445. Said shoes are interchangeable, and are fastened to guide-plate by means of screws e e.

26 is a straight feed-rack pivoted to feed-slide 1 at 27, and rests in a milled groove or recess 28 in said feed-slide 1. (See Fig. 1, 80 Plate 1.)

29 is a movable rod carried in slotted bearing 30, fastened to under side of feed-slide 1 by means of screw f. (See Fig. 1, Plate 1.)

31 is a coiled-wire spring, which presses rod 85 29 forward in the direction of side bearing Q of bed-plate A, on which bearings Q Q feed-slide 1 rests. (See Fig. 10, Plate 4.)

32 and 33 are notches cut in one of the side bearings Q of bed-plate A. (See Fig. 10, Plate 4.) Notch 32 is simply to make room for said movable rod 29 when feed-slide 1 is placed in position on bearings Q Q. When feed-slide 1 reaches the point where the round end of the eye of the button-hole is to be made, pawl 95 18 is lifted from ratchet-wheel 17, and feed-slide 1 stops. Feed-cam or sectional part of worm 11 engages pivoted tooth 4, and disk 2 is intermittently turned. To hold feed-slide 1 steady during the process of turning disk 2, 100 rod 29 enters notch 33 and prevents any forward movement of said slide 1 under the action of feed-cam or sectional part of worm 11.

34 is a pin on the end of rod 29. On the last movement of disk 2 in the process of turning in stitching the round end of the eye of the button-hole projection 7 on pivoted tooth 4 in segmental rack 3 comes in contact with pin 34 on the end of rod 29, and thus the latter is forced back out of notch 33 in bed-plate 110 A, and feed-slide 1 is again permitted to move forward in stitching the last straight side of the button-hole.

Fig. 18, Sheet 5, shows rod 36 with right and left hand screw-threads O O cut thereon and carrying two movable blocks 37 and 38. These two blocks 37 and 38 extend both above and below bed-plate A through slots P P, Fig. 10, Plate 4, and Fig. 6, Plate 2. Block 37 has a beveled edge a⁴, as shown in Fig. 18, Plate 5, and Fig. 10, Plate 4. Blocks 37 and 38 serve as stop-motions for controlling the beginning and ending of the stitching in each button-hole, and likewise the length of same. By turning rod 36 the two blocks 37 and 38 are 125 drawn together or carried apart, according to the desired length of the button-hole.

As shown in Fig. 1, Plate 1, and Figs. 23, 24, and 25, Plate 5, 35 is a projection or lug fastened to upper side of feed-slide 1 and 130 extending over the edge of same. After the fabric has been clamped and cut for the button-hole feed-slide 1 is pushed forward until lug 35 comes in contact with block 37,

carried on rod 36, as shown in Fig. 23, Plate 5. The distance the feed-slide is permitted to move forward until lug 35 comes in contact with block 37 controls the beginning of the stitching in the desired length of button-hole, and this distance is regulated by the operator moving block 37 on rod 36 by means of screw O.

When the machine is thrown into gear by the operator pressing upon trip-rod D, carrying button D', (see Figs. 4 and 5, Plate 2,) which is pivoted to trip-lever 83 at a⁴⁴ by pin a⁵, (see Figs. 4 and 5, Plate 2,) lever 40 by its incline 40 $\frac{1}{2}$ (see Fig. 19, Plate 5) is oscillated. Lever 40, which is pivoted to bed-plate A by a stud and screw 41 $\frac{1}{2}$, in turn oscillates or moves block 37 out of line of lug 35, as shown in Fig. 24, Plate 5, and thus feed-slide 1 is permitted to move forward until lug 35 on feed-slide 1 reaches block 38, as shown in Fig. 25, Plate 5. Block 38 is pushed over by the pressure of lug 35. By this action the lower end of block 38 is made to press against lever 41. Lever 41 in turn presses against trigger or trip 42, as shown in Fig. 21, Plate 5, and Figs. 4 and 5, Plate 2, forcing it off its resting-point on bed-plate A at S, thus tripping and stopping the machine by the action of the stop-motion hereinafter more fully described. Spring 39, attached to block 37, (see Fig. 18, Plate 5,) restores said block 37 to its upright position as soon as the machine is tripped and stopped; but the beveled edge on block 37 permits lug 35 to push it over and pass, when the feed-slide is brought back and returned to its initial position after each button-hole has been stitched.

11 is what is known in mechanism as a "feed-cam" or "sectional part of a worm," carried on main shaft B. (See Figs. 2 and 3, Plate 1, and Fig. 9, Plate 3, and Fig. 10, Plate 4.) A portion of said feed-cam is cut away, as shown in Fig. 8, Plate 2, and Fig. 9, Plate 3, to give it intermittent engagement with segmental rack 3, and to enable disk 2 to be turned and brought back to its initial position after the stitching has been completed in each button-hole, and therefore may be properly called a "feed-cam" or "sectional part of a worm." The feed-cam gears in segmental rack 3, fastened to under side of disk 2, and intermittently turns disk 2 after each stitch has been completed in stitching the round end of the eye of the button-hole. A curvature a⁶ in the flange or blade of feed-cam or sectional part of worm 11, as shown in Fig. 9, Plate 3, turns disk 2, and at the same time controls the distance of each intermittent turn of said disk 2 at each revolution of shaft B, and as each stitch is made in the round end of the eye of the button-hole. The other portion of the blade or flange of said feed-cam or sectional part of worm 11 is straight and serves to lock and hold said disk 2 steady after each intermittent movement has been made by the action of feed-cam or sectional part of worm 11.

43 is a projection on bed-plate A, having screw 44. (See Figs. 6 and 8, Plate 2.) The object of screw 44 is to control the quantity of cloth embraced inside the line of action of the needle in stitching the round end of the eye of the button-hole.

In heavy materials a less quantity is needed inside the line of the needle than where the material is light, and screw 44 serves to regulate this at the will of the operator when cutting the hole in the fabric. When the feed-slide 1 is pulled back to cut the hole in the material, lug 35, fastened to feed-slide 1, comes in contact with the end of screw 44. By lengthening or shortening screw 44 the quantity of material left inside the radial action of the needle can be regulated. In other words, the further back the slide is permitted to come the more material there will be between the line of action of the needle and the edge of the cut, and vice versa.

Fig. 10, Plate 4, is a view of the upper side of the bed-plate A with feed-slide removed.

16 is a plate to which the center or throat plate 2 is fastened, and is held in place by screws i i i.

10 is a small plate fastened to plate 16, and by means of which pivoted tooth 4 of segmental rack 3 is held above the outer periphery of feed-cam or sectional part of worm 11 while being fed forward in stitching the first straight side of the button-hole. (See Fig. 3, Plate 1.)

10 $\frac{1}{2}$ is a projection or elevation on the side of plate 10, against the side of which pivoted tooth 4 of segmental rack 3 presses when the fabric is being cut, preventing disk 2 from turning, and thereby securing a straight cut in the fabric.

24 is a stud-carrying roller c', that works in slot 23 in feed-guide 22, fastened to the under side of feed-slide 1, and thus controls and gives direction to the latter. (See Plate 1, Fig. 1.)

24 $\frac{1}{2}$ is an adjustable slide with beveled edges, to which stud 24, carrying roller c', is fastened. This slide is held between two beveled pieces 45 45, fastened to bed-plate A by screws h h h h.

g is a set-screw for holding adjustable slide 24 $\frac{1}{2}$ in place.

46 is an adjustable slide working in beveled bearings 47 47 on bed-plate A. (See Fig. 10, Plate 4.)

48 is a swiveled guide or bearing fastened to slide 46 by screw 49.

50 $\frac{1}{2}$ is a set-screw in slide 46.

50 is a swiveled guide or bearing fastened to bed-plate A by screw 51. These two swiveled guides or bearings 48 and 50 enter grooves E E (see Fig. 1, Plate 1) on sides of feed-slide 1, and hold it in place. The slide 1 therefore rests on the bearings Q Q, and is grasped between the swiveling guides 48 and 50, its angular position being governed by the slot in guide-plate 22 and the shoes 25 25, which are

attached to said plate, and between which the pin 24 projects. The slide 1 is kept in operative engagement with the gear-wheel 57 irrespective of any change in its angular position by the device of pivoting the rack 26 at one end, as shown, and allowing it to turn freely on said pivot. In this way the said rack always maintains the same alignment irrespective of the change in the angular position of the slide to which it is pivoted and which is drawn forward.

52 is a slotted bridge on the side of throat-plate 21. 53 is a pin working in said slotted bridge 52, which, by the combined action of lever 54, fastened to center plate 16 by screw 54½, roller 55, working in cam-groove 56, is intermittently thrust between the two needles on their upward movement. By this means pin 53 is made to catch the thread of the upper needle on each upward movement and hold it in the throat or center plate until after the upper needle has reached its highest point of elevation. When the stitching of the button-hole has been completed, the thread of the upper needle is cut, and as the material is taken from beneath the clamp the end of the thread attached to the button-hole being held by pin 53 the end is drawn down through the goods, and thus the last loop in the stitching is destroyed and the button-hole will not unravel. Application for Letters Patent by E. B. Moore and George Rehfuss covering this mechanical device are now pending in the Patent Office. The Serial number of the application is 227,716.

57 is a gear-wheel carried on shaft a^7 , (see Plate 2, Fig. 8,) and extends above bed-plate A, and to which straight gear-rack 26, carried on under side of feed-slide 1, is connected. (See Plate 1, Fig. 1, and Plate 4, Fig. 10.)

Fig. 11, Plate 4, is a perspective view of plate 16 and throat-plate 21, and to which is fastened plate 10.

57½, Fig. 12, Plate 4, is a perspective view of block with beveled grooves 58 and 59 on opposite sides of said block. Needle-racer 62 is operated in groove 58.

59½ is a stud with thread cut on the end, and by which means said grooved block 57 is swiveled to bed-plate A.

60 is a pin or stud on the end of block 57 and carries roller 60½. Roller 60½ works in side cam 61, having groove 61½. The object of roller 60½ and cam 61 is to vibrate one end of block 57½, and thus throw the lower needle on one side of the upper needle when they are both below the throat-plate, and on the opposite side thereof when they are both above the throat-plate. This principle of vibrating the block carrying lower needle-racer has been made the subject for Letters Patent by E. B. Moore and George Rehfuss. The Serial number of the application is 202,568.

62, Fig. 13, Plate 4, is a perspective view of needle-racer with beveled sides carrying needle 69, operated in groove 58 in block 57½.

63 is a washer that moves in groove 59 in block 57½.

64 is a slot in block 57½. By means of a screw passing through washer 63 and slot 64 and fastened to beveled needle-racer block 62, the latter is held firmly in groove 58 in block 57½ while being moved backward and forward in the process of stitching the button-hole.

65 is a part of needle-racer arm with ball-joint 66, which is attached to needle-racer block 62 by means of pins 67 and nut 68.

69 is the lower needle, held in place by block 70 and screw 71.

65, Fig. 14, Plate 4, is a perspective view of opposite end of needle-racer arm 65, having ball-joint 73 and screw 74.

75, Fig. 15, is a perspective sectional under side view of one of the levers for operating lower needle, its functions being more clearly represented on Plate 3, Fig. 9.

76 is a slot in said lever 74, in which slide 77 is operated. (See Plate 3, Fig. 9.)

78 is an adjustable side bearing. (See, also, Plate 3, Fig. 9.)

79 is a hole for screw 74 in ball-joint 73. (See Fig. 15, Plate 4.)

80 is a washer on pin 82.

81 is a nut on one end of pin 82, that passes through slide 77. (See Fig. 9, Plate 3.)

Figs. 4 and 5, Plate 2, are sectional views of under side of machine, as shown at w w , Plate 3.

83 is a trip-lever, pivoted at X, and hinged or linked to lever 84 at Y.

85 is a shaft or rod for stop-motion.

II, Fig. 9, Plate 3, is the lower take-up operated by cam II'.

86 is a face-cam carried on main shaft B, having groove 89. (See Plate 3, Fig. 9.)

87 is an arm-carrying roller 88, (see Fig. 4, Plate 2,) that moves in groove 89 of cam 86. (See Fig. 9, Plate 3.)

90 is a nut on end of pin and screw 91 of roller 88. (See Fig. 4, Plate 2.) 91½ is a washer on said pin and screw 91. (See Fig. 9, Plate 3.) Arm 87 is pivoted to bed-plate at one end by screw 92, and is connected at the other end with lever-arm 75 by means of slide 77 and pin 82. (See Fig. 9, Plate 9.) Arm 75 is fastened to bed-plate by stud and screw 93. By the combined action of levers 75 and 87, cam 86, with roller 88, working in groove 89, and lever 65, needle-racer 62, carrying lower needle 69, is operated in groove 58 of block 57½. (See Figs. 9, Plate 3, and Figs. 11, 12, 13, 14, and 15, Plate 4, and Fig. 4, Plate 2.)

94 is a brake made of tempered steel faced with leather, and is intended to steady the movement of feed-slide 1 under the action of pawl 18, working in ratchet-wheel 17. This brake is screwed to trip-arm 84 through block 84½ by means of screws K K.

95 is a wheel carried on ratchet-wheel shaft 125, against which brake 94 impinges.

Fig. 4, Plate 2, shows the machine in a

tripped condition. The end of trigger 42, pivoted to trip-arm 83, has been removed from its bearing on bed-plate A, at S, by the action of trip-lever 41. (See, also, Fig. 21, Plate 5.) Trip-pin D, carrying button D', is elevated above surface of bed-plate A, trip-lever arm 84 is forced down, as at Y, and brake 94 by this same action is removed from contact with wheel 95. Fig. 5, Plate 2, shows the machine in a geared condition, trip-pin D, with button D', is forced down even with the surface of bed-plate A, and the end of trigger 42 is resting on projection of bed-plate A at S, being pushed forward by the action of spring 97 when arm 83 is depressed.

Fig. 6, Plate 2, is a sectional view of lower side of machine, as at X X, Plate 3. 97½ is a cam operated on main shaft B and moved in feed-block 98, having arms 99 99. Feed-block 98 has beveled sides, and is held in place by beveled side pieces 100 100, as shown in Fig. 7, Plate 2.

101 is a link pivoted on ratchet-wheel shaft 96. This pivoted link has a slot 102, in which 25 is operated slide-block 103, fastened to feed-slide 98 by means of a stud and nut passing through arm of feed-block 98, which has a slot corresponding to slot 102. Pawl 18 is pivoted to an arm of link 101 at 104. Thus by the action of eccentric-cam 97½, working between arms 99 99 of feed-block 98, a backward and forward movement is imparted to feed-block 98. At the same time a rocking motion is imparted to the link 101, carrying pawl 18, which 35 through its action on ratchet-wheel 17, a forward step-by-step movement is given to said ratchet-wheel 17 and shaft 96 is turned. Through gear-wheel 57½, carried on shaft 96, and gear-wheel 57, carried on shaft a, (see Fig. 9, Plate 3, and Fig. 8, Plate 3,) and their connection with straightfeed-rack 26, carried on feed-slide 1, a forward step-by-step movement is imparted to said feed-slide 1 after each 40 stitch has been completed. By raising or depressing slide-block 103 in slot 102 a longer or shorter throw can be given to pawl 18, and thus the length of movement of link-arm 101 under the action of cam 97½, working in feed-block 98, can be controlled, and by this means 45 the number of stitches in a button-hole can be regulated. Spring 105 keeps pawl 18 in ratchet-wheel 17.

Fig. 17, Plate 5, gives a perspective view of the means by which pawl 18 is lifted from the ratchet-wheel 17 at the conclusion of the stitching of each button-hole.

106 is a lever pivoted to stud 85½ on bed-plate A by screw 109. (See Fig. 9, Plate 2.) One arm of lever 106 is numbered 107 and the 50 other 108. (See Figs. 4, 5, 6, and 8, Plate 2, and Fig. 9, Plate 3, and Fig. 22, Plate 5.) Arm 107 extends under pawl 18 of ratchet-wheel 17, while the other arm 108 extends under block 84½ of trip-lever arm 84. (See Figs. 17 and 22, 55 Plate 5, and Fig. 9, Plate 3, and Figs. 4 and 5, Plate 2.) When the machine is tripped and out of gear, trip-lever arm 84 is depressed, and

block 84½ coming in contact with arm 108 of lever 106, arm 107 is moved, and by this action pawl 18 is removed from ratchet-wheel 17, as shown in Fig. 8, Plate 2. When pin D is pressed down by the operator, lever 84 is raised, releasing arm 108, and pawl 18 is restored to engagement with ratchet-wheel 17 by the action of spring 105. (See Figs. 22 and 75 17, Plate 5, and Fig. 6, Plate 2.)

Fig. 26, Plate 5, is a rear view of head of arm of machine.

110 is the arm of machine.

111 is the rock-shaft for operating needle-bar 112.

113 is a sectional part of head of arm. (See Fig. 27, Plate 6.)

114 is a wedge, which separates the two sectional parts 110 and 113 of the head of the 85 machine, as shown in Fig. 28, Plate 6.

115 115 are two screws that hold the two sectional parts 110 and 113 together. There are two slots (not shown) in wedge 114, which admit of the passage of screws 115 115. These 90 slots are sufficiently elongated to admit of raising or lowering wedge 114 by means of screw 116, which rests upon a slotted plate 117. There is a groove underneath the head of screw 116, in which plate 117 rests. This 95 groove holds screw 116 in place and secures its desired action upon wedge 114. The object of wedge 114 is to move the needle-bar holding needle laterally. (See Fig. 26, Plate 5, and Figs. 27 and 28, Plate 6.)

E. B. Moore and George Rehfuss have made application for Letters Patent covering this mechanism for moving needle-bar laterally. Serial number of application 202,568.

118, 119, 120, and 121 are ordinary links and 105 pins for connecting needle-bar 112 with rock-shaft 111.

122 is the upper take-up; 123, the bearing on arm of machine for take-up.

124 is a lever-carrying stud 125 and roller 110 126, working in groove 127 of cam 128, carried on rock-shaft 111.

129 129 are pieces forming cam 128, and are held in their respective places by screws c³ c³ c³ c³.

Fig. 28, Plate 6, shows among other things a skeleton side view of the machine resting upon its iron stand G, which is screwed to the table or support upon which the whole rests.

130½ is a cutting-knife secured, as shown, on a lever 130 131, pivoted at 132, and, as shown, made up of two parts 130 and 131, which parts may be made adjustable upon each other in any convenient way.

134 is a movable block beveled at 135 on its 125 upper side, and is held in place by beveled side pieces on bed-plate A. One end of beveled block 134 rests on anvil 136, which is fastened to the table or support to which the iron stand is fastened.

137 is a lever or arm to which is fastened block 138 by means of set-screw 139. Lever-arm 137 is pivoted between brackets on bed-plate A at 140.

141 is a rod, one end of which is swiveled to block 134 by a screw 142, while the other end of said rod is fastened to arm 137 by a screw 143. As lever-arm 137 is depressed for 5 cutting the button-hole, block 134 is drawn out over anvil 136, and by means of beveled edge 135 on block 134 block 130 is raised until knife 130 $\frac{1}{2}$, carried on said block, 134 is raised up until it comes in contact with the 10 fabric that is to be cut.

144 is a spiral spring, one end of which is attached to bed-plate A at 145 and the other end to lever-arm 137 at 146. As soon as the 15 blow has been administered by the descent of lever-arm 137, carrying cutting-block 138 and the fabric cut, lever-arm 137 is carried up and block 134 forced back to position shown in drawings, and block 130, carrying knife, is forced down by action of spring 147.

20 The advantage of this cutting device is that while the cutting is quickly executed the fact that the anvil rests upon the table or support of the machine furnishes a thoroughly solid basis for the action of the cutting-block, and at the same time removes all 25 jar or shock to the machine itself. It is believed to be an improvement upon a cutting device for which Letters Patent No. 314,046 were granted to E. B. Moore under date of 30 March 17, 1885.

148 and 149, Plate 3, Fig. 9, and Figs. 29 and 33, Plate 1, represent fast and loose pulleys on main shaft B.

152 is a recess or slot in fast pulley 149. 153 35 is a stop and feed-rod in said slot 152, carrying spiral spring 154 and screw 155, the latter to control the tension of said spring 154. (See Fig. 29, Plate 1.) Upon the side of loose pulley 148 there is a flange 156. (See Figs. 29 40 and 33, Plate 1.) The end of the stop and feed-rod 153 is recessed, as at 157, (see Fig. 29, Plate 1,) and when the machine is in motion extends above the outer periphery of fast pulley 149, and against which flange 156 on 45 loose pulley 148 impinges, and by that means motion is imparted to the machine.

158, Plate 3, Fig. 9, is a boss on the under side of bed-plate A, (shown partly in section,) for exposing rod 159 and spring 160, and 50 recess or counterbore 161. Attached to rod 159 is a cap or trip 162, the under surface of which corresponds in general curvature to the circular form of loose pulley 148, except one end of which is slightly elevated, as at a $\frac{1}{2}$, Fig. 29, 55 Plate 1. This cap or trip 162 occupies a position near the outer edge of pulley 149 and on a line with it.

163 is a lever fastened to rod 159, having slot 164. (See Fig. 31, Plate 1.) 60 165 is a short lever fastened to rod 85, one end of which passes through slot 164 in lever 163. (See Figs. 31 and 32, Plate 1, and Fig. 9.) 166 is an eccentric carried on main shaft B, that moves the needle-bar by means of rock-shaft 111. (See Fig. 9, Plate 3.)

167 is a cam on eccentric 166. (See Fig. 32, 65 Plate 1.) When the machine is tripped at

the conclusion of the stitching of the button-hole, lever 163 is dropped upon main shaft B by the action of lever 165 on rod 85, the 70 end of lever 163 comes in the path of cam 167 on the side of eccentric 166, causing rod 159 to move laterally, cap or trip 162 by the same action is moved over the outer periphery of fast pulley 149, and the end of stop and feed 75 rod 153 coming under the raised end of cap or trip 162 at a $\frac{1}{2}$ the end of stop and feed rod 153 is forced downward, and thus the latter is released from an engagement with flange 156 on loose pulley 148, and by which 80 operation the machine is stopped. There is a notch or recess a $\frac{1}{2}$ in cap or trip 162, into which stop and feed rod 153 raises after being depressed to secure the accurate stoppage of the machine at that point; but it is not permitted to rise high enough to impinge against flange 156 on loose pulley 148. The longer arm of this offset comes under cap 162, and is depressed until the lower part is carried below the outer periphery of pulley 149, and 85 at the same time releasing said rod from impingement with flange 156 on loose pulley 148. When rod D, carrying button D', is depressed, (see Fig. 5, Plate 2,) rod 85 is oscillated through its connection with link 84, (see Figs. 95 4 and 5, Plate 2,) and by which action lever 163 is released from impingement with cam 167, when by the action of spring 160 on rod 159 the latter is again moved laterally, and by which means cap or trip 162 is removed 100 from the outer periphery of fast pulley 149, and stop and feed rod 153 is raised by the action of spring 113 and placed in position for engagement with flange 156 on loose pulley 148, and motion is thus at once imparted 105 to the machine.

Having described the various parts, what we claim to be our invention, and for which we desire to secure Letters Patent, is—

1. In a button-hole sewing-machine, a feed-slide, in combination with a rotating plate secured upon said slide, a segmental circular rack attached to said plate, gearing adapted to engage said rack and rotate the plate through a determined arc, and a movable 110 rack-tooth secured to the plate and arranged to engage the driving-gear and throw it into operative connection with the rack.

2. In a button-hole sewing-machine, the combination, with the feed-slide, of a rotating plate secured upon said slide, a segmental circular rack attached to said plate, and a rotating cam having the forward part of its acting-surface made like a section of a screw and the rear portion formed in a plane perpendicular to its axes of rotation, so that when engaged with the rack it first turns the plate for a determined distance and then holds it stationary during the rest of each revolution of the cam, substantially as and for the purpose specified.

3. In a button-hole sewing-machine, the combination, with the feed-slide, of a rotating plate secured upon said slide, a segmental

5 circular rack attached to said plate, a rotating feed-cam arranged to engage said rack and rotate the plate through a determined are, and a movable tooth secured to said plate and by which the rack and cam are thrown into gear.

10 4. In a button-hole sewing-machine, the combination, with the feed-slide, of a rotating plate secured upon said slide, a segmental 70 circular rack attached to said plate, a rotating feed-cam arranged to engage said rack and rotate the plate through a determined are, a movable rack-tooth pivoted to said plate and arranged when depressed to engage the 75 cam and throw it into engagement with the rack, and a tooth-supporting plate secured to the frame of the machine and arranged to hold the movable tooth up for a determined part of the forward motion of the feed-slide.

15 5. In a button-hole sewing-machine, a feed-slide, in combination with a rotating plate secured in said slide, a circular segmental rack attached to said plate, a movable rack-tooth attached to the end of a lever pivoted to the 20 plate, a depressing-rod attached to the other end of the said lever and extending through the plate, and a rotating cam arranged to engage the rack by means of its movable tooth when said tooth is pressed down, all substantially as and for the purpose specified.

25 6. In a button-hole sewing-machine, the combination, with the feed-slide, of mechanism for actuating the same, as described, operated by a ratchet-wheel, a pawl actuated by the continuously-operating parts of the machine, a pawl-lifting device arranged, as described, to lift said pawl out of contact with the ratchet-wheel and stop the forward feed 30 of the slide and having an actuating-pin 13, situated beneath and near the end of the slide in the direction to which it moves, a rotating plate secured in the slide, a circular segmental rack attached to said plate, a movable rack-tooth secured at the front end of the 35 slide, gearing arranged to drive the plate by means of the rack and placed so as to be thrown into gear therewith by means of the movable tooth, a plate arranged to come in contact with and raise pin 13, and through it the pawl aforesaid, at a determined point in the forward movement of the slide, and a flange extending around the periphery of the rack, as described, and acting to hold pin 13 up and 40 stop the motion of the slide while the plate is rotating, all substantially as and for the purpose specified.

45 7. In a button-hole sewing-machine, the combination, with the feed-slide, of mechanism for actuating the same, as described, operated by a ratchet-wheel, a pawl actuated by the continuously-operating parts of the machine, a pawl-lifting device arranged, as described, to lift said pawl out of contact with the ratchet-wheel and stop the forward feed 50 of the slide, and having an actuating-pin 13, situated beneath and near the end of the slide in the direction to which it moves, a rotating 55 plate secured in the slide, a circular segmental rack attached to said plate, a movable rack-

tating plate secured in the slide, a circular segmental rack attached to said plate, a movable rack-tooth secured at the front end of the 70 rack, gearing arranged to drive the plate by means of the rack and placed so as to be thrown into gear therewith by means of the movable tooth, a plate arranged on the front end of the movable tooth to come in contact with and raise pin 13, and through it the pawl aforesaid, at a determined point in the forward movement of the slide, and a flange extending around the periphery of the rack, as described, and acting to hold pin 13 up and 75 stop the motion of the slide while the plate is rotating, all substantially as and for the purpose specified.

8. In a button-hole sewing-machine, the combination, with the feed-slide carrying a rotating disk, and the bearings on which said slide moves, of a spring-pin 29, secured to the bottom of the slide so as to press against one of the bearings thereof, and a notch 33, formed in said bearing to receive the pin and lock 90 the slide in position while its rotating plate is in operation.

9. In a button-hole sewing-machine, the combination, with the feed-slide, of mechanism for actuating the same, as described, operated by a ratchet-wheel, a pawl actuated by the continuously-operating parts of the machine, a pawl-lifting device arranged, as described, to lift said pawl out of contact with the ratchet-wheel and stop the forward feed 100 of the slide and having an actuating-pin 13, situated beneath and near the end of the slide in the direction to which it moves, a rotating plate secured in the slide, a circular segmental rack attached to said plate, a movable rack-tooth secured at the front end of the 105 rack, gearing arranged to drive the plate by means of the rack and placed so as to be thrown into gear therewith by means of the movable tooth, a plate arranged to come in contact with and raise pin 13, and through it the pawl aforesaid at a determined point in the forward movement of the slide, a flange extending around the periphery of the rack, as described, and acting to hold pin 13 up and 110 stop the motion of the slide while the plate is rotating, and a locking-pin, as 29, arranged to register with and engage a notch at the moment the pawl is lifted from the ratchet-wheel, so as to lock the slide in position, all 115 substantially as and for the purpose specified.

10. In a button-hole sewing-machine, the combination, with the feed-slide, of mechanism for actuating the same, as described, operated by a ratchet-wheel, a pawl actuated by 120 the continuously-operating parts of the machine, a pawl-lifting device arranged, as described, to lift said pawl out of contact with the ratchet-wheel and stop the forward feed of the slide, and having an actuating-pin 13, 125 situated beneath and near the end of the slide in the direction to which it moves, a rotating plate secured in the slide, a circular segmental rack attached to said plate, a movable rack- 130

tooth secured at the front end of the rack, gearing arranged to drive the plate by means of the rack and placed so as to be thrown into gear therewith by means of the movable tooth, 5 a plate arranged to come in contact with and raise pin 13, and through it the pawl aforesaid, at a determined point in the forward movement of the slide, a flange extending around the periphery of the rack, as described, and 10 acting to hold pin 13 up and stop the motion of the slide while the plate is rotating, a notch 33, formed in the edge of a slide-bearing, a spring-pin 29, arranged to engage said notch and lock the slide in position when the pawl 15 is lifted from the ratchet-wheel, and a plate secured upon the rotating disk and situated, as described, so that it will engage pin 29 and withdraw it from the notch as the rotation of the plate is complete, all substantially as and 20 for the purpose specified.

11. In a button-hole sewing-machine, the mechanism for carrying and actuating the lower needle, consisting of a grooved block 57 $\frac{1}{2}$, pivoted at one end, a needle-carrier 71, 25 secured in the groove of block 57 $\frac{1}{2}$, a cam 61 $\frac{1}{2}$, arranged to engage the free end of block 57 $\frac{1}{2}$ and give it one oscillating movement, as described, a pivoted lever 87, a cam 86, acting to oscillate said lever, a pivoted slotted lever- 30 arm 75, connected to lever 87 by slide-block 77, and a rod 65, connecting lever 75 with the needle-carrier, all substantially as specified.

12. In a button-hole sewing-machine having a clutch arranged to connect and disconnect 35 the main shaft and driving-wheel, the combination of the feed-slide with a lug 35, extending out from one edge thereof, a rotating rod 36, having right and left screw-threads cut upon it, a stop-block 37, swiveling upon the 40 threaded end of the rod nearest the front of the machine and adapted to engage lug 35 when turned in toward the slide, and a clutch-locking block 38, swiveling on the threaded end of rod 36 farthest from the front of the 45 machine, said clutch-locking block 38, when turned in toward the slide, locking the clutch connecting the main shaft with the driving-wheel in operative position, and being adapted to engage lug 35 so as to be pushed out by 50 lug 33, thus stopping the machine, all substantially as and for the purpose specified.

13. In a button-hole sewing-machine having a clutch arranged to connect and disconnect the main shaft and driving-wheel, the 55 combination of the feed-slide with a lug 35, extending out from one edge thereof, a rotatable rod 36, having right and left screw-threads cut upon it, a stop-block 37, swiveling upon the threaded end of the rod nearest the front 60 of the machine and adapted to engage lug 35 when turned in toward the slide, a clutch-locking block 38, swiveling on the threaded end of rod 36 farthest from the front of the machine, said clutch-locking block 38, when 65 turned in toward the slide, locking the clutch connecting the main shaft with the driving-wheel in operative position, being adapted to

engage with lug 35 so as to be pushed out by lug 35, thus stopping the machine, and mechanism arranged, as described, to push the 70 stop-block 37 in when the clutch is out of action.

14. In a button-hole sewing-machine, the combination of the feed-slide, a lug 35, carried on the edge of said slide, a rod 36, having screw-threads O O cut thereon in opposite directions, a stop-block 37 and latching-block 38, swiveling on said rod, as specified, a trip-lever 83, trip-rod D, lever 84, stop-lever 85, levers 40 and 41, the former having beveled edge 41 $\frac{1}{2}$, trip-dog 42, and spring 97, all combined to act in starting and stopping the machine, as specified.

15. In a button-hole sewing-machine, the combination of the feed-slide, a lug 35, extending out from said slide, a lug 43, secured to the bed-plate, and an adjustable stop 44, screwing in said lug and arranged in the path of lug 35, so as to regulate the backward motion of the slide.

16. In a button-hole sewing-machine, the combination, with the gear-wheel 57 and its actuating mechanism, of the feed-slide and a straight rack 26, pivoted at one end to the slide and having a free pivotal engagement 95 with the gear-wheel 57, whereby the slide can change its angular position without change in the position of the rack.

17. In combination with the stitch-forming mechanisms of a button-hole sewing-machine, 100 feed-slide 1, pivoted straight feed-rack 26, feed-wheel 57, carried on shaft a, intermediate feed-wheel 57 $\frac{1}{2}$, carried on shaft 96, arm 101, having slot 102 and carrying slide-block 103, pawl 18, pivoted to arm 101, feed-block 105 98, having arms 100 100, cam 97 $\frac{1}{2}$, carried on main shaft B, whereby by the combined action of these several parts a forward step-by-step motion is imparted to feed-slide 1, as fully set forth and described.

18. In combination with the stitch-forming mechanisms of a button-hole sewing-machine, feed-slide 1, feed-rack 26, feed-wheel 57, shaft a, and intermediate feed-wheel 57 $\frac{1}{2}$, shaft 96, ratchet-wheel 17, pawl 18, trip-pin D, and levers 83 and 84, block 84 $\frac{1}{2}$, wheel 95 on shaft 96, brake 94, for the purposes of securing regular movements to feed-slide 1 under the action of pawl 18, working in ratchet-wheel 17, as fully set forth and described.

19. In a button-hole sewing-machine, in combination with a shaft and mechanism actuated by said shaft acting to move the feed-slide, a ratchet-wheel 17, secured to said shaft, a brake-wheel 95, connected to said shaft, a 125 rock-lever 101, a pawl 18, attached to said lever and arranged to engage the ratchet-wheel, a cam 97 $\frac{1}{2}$, and mechanism connecting said cam with lever 101, a pivoted trip-lever 84, a brake 94, secured to said trip-lever so as to 130 overlie brake-wheel 95, a pivoted lever 106, having one arm 108 arranged with reference to the trip-lever, as described, and its other arm 107 extending beneath pawl 18, and mech-

anism for actuating trip-lever 84, as described, so that when said lever is depressed the brake is applied to wheel 95, and the pawl restored to the ratchet-wheel 17.

5 20. In a button-hole sewing-machine, in combination with a shaft and mechanism actuated by said shaft acting to move the feed-slide, a ratchet-wheel 17, secured to said shaft, a brake-wheel 95, connected to said shaft, a rock-lever 101, a pawl 18, attached to said lever and arranged to engage the ratchet-wheel, a cam 97 $\frac{1}{2}$, and mechanism connecting said cam with lever 101, a pivoted trip-lever 84, a brake 94, secured to said trip-lever so as to 10 overlie brake-wheel 95, a pivoted lever 106, having one arm 108 arranged with reference to the trip-lever, as described, and its other arm 107 extending beneath pawl 18, and a second strip-lever 83, arranged, as described, 15 to actuate lever 84, all substantially as and for the purpose specified.

20 21. In a button-hole sewing-machine, a pivoted arm 131, carrying one of a pair of cutters, a sliding wedge 134, arranged to elevate

and support the arm 131, an anvil 136, arranged to support said wedge, a lever-arm 137, pivoted to the machine at one end and carrying a cutter, a rod 141, connecting the wedge with an arm of lever 137, and a spring arranged to hold the arm 137 raised, all substantially as and for the purpose specified. 25

22. In a button-hole sewing-machine, a pivoted arm 131, carrying one of a pair of cutters adjustably secured to it, a sliding wedge 134, arranged to elevate and support the arm 30 35 131, an anvil 136, arranged to support said wedge, a lever-arm 137, pivoted to the machine at one end and carrying a cutter, a rod 141, connecting the wedge with an arm of lever 137, and a spring arranged to hold the arm 40 45 137 raised, all substantially as and for the purpose specified.
